UNITED STATES PATENT OFFICE

MONROE GUETT, OF HARTFORD, CONNECTICUT, ASSIGNOR TO THE ARROW-HART & HEGEMAN ELECTRIC COMPANY, OF HARTFORD, CONNECTICUT, A CORPORATION OF CONNECTICUT

SECURING MEANS FOR ELECTRICAL CONNECTERS

Application filed November 6, 1930. Serial No. 493,868.

This invention relates to electric connecting devices, more particularly it relates to quick detachable connectors provided with socket contacts which are adapted to cooperate with contact fingers which project from an electrical translating device.

Heretofore this type of connector has commonly been made of two similar halves which have been secured together either by nuts and bolts piercing the two halves or by a metallic band surrounding them. The nut and bolt method had the disadvantage that the bolt loosened and had to be repeatedly tightened; and the metallic bands have not been wholly satisfactory.

It is an object of my invention to provide a more simple securing means which may be removed and replaced more quickly than the prior securing devices and which can be manufactured very cheaply.

In the drawing:

Fig. 1 is a view of the feed line end of a connector having a switch mechanism incorporated therein and having its halves held together by a modified form of my securing means.

Fig. 2 is a view of the contact-finger-receiving end of the connector shown in Fig. 3.

Fig. 3 is a section view of the connector and securing means shown in Figs. 1 and 2, the section being taken at right angles to the divisional plane between the two halves of the connector.

Referring to the drawing, Figs. 1, 2 and 3 show a conventional connector having similar complementary halves 10 and 12 made of an insulating composition and having cavities 14, 16 molded in one surface thereof to receive the usual electrical switch mechanism. The connector shown is of the switch type, the switch thumb piece being indicated at S in Figs. 1 and 2.

Upon fitting the halves of the connector together a flattened tube is formed. Into an aperture 31 at one end thereof feed wires are customarily led while twin apertures 34 and 35 at the other end permit the contact fingers of an electrical device to enter and engage the socket contacts (not shown) within the connector.

According to my invention the halves of the connector are held together at one end by a split metal ring 32 which possesses the characteristics of stiffness and resiliency. The ring fits snugly around a cylindrical nub 30, 55 which defines the feed wire aperture 31. One half of the nub 30 is formed on each half of the connector at the feed wire aperture. To hold the ring in place around the nub, a bead or the like may be formed around 60 the top of the nub.

Each half of the connector has cut in it at the outer end an L-shaped channel 33 extending down the side of the connector around the edge to a position between the contact apertures, 34 35. The channel in one half of the connector registers with that of the other half and there is seated in the continuous passage thus formed a metallic U-shaped spring clip 36. The legs of this clip bearing against the bottom of the channel press the two halves of the connector together at the contact receiving end thereof.

The spring clip 36 and the ring 32 may be cut from steel wire. Thus the cost of the connector is reduced without impairment of quality over prior connectors. From the foregoing it will be apparent that I have provided a simple, secure means to hold the halves of a connector together, which means 75 may be quickly removed and replaced without the necessity for the use of the customary tools.

I claim:

1. An electrical connecting device comprising a casing formed of a plurality of parts and having a substantially circular channel formed therein adjacent to one end of said device and a substantially U-shaped channel formed therein adjacent the other end of said device, portions of each of said channels being located in each of said parts, a spring ring engaging in said circular channel and a spring clip engaging in said U channel where- 85 by said parts are held together.

2. An electrical connecting device comprising a casing formed of a plurality of parts and having a substantially circular channel formed therein and a substantially U-shaped channel formed therein, portions of 95 100

each of said channels being located in each of said parts, said circular channel being formed around the feed wire opening and said U channel being formed between the contact apertures of the device, a ring engaging in said circular channel and a spring clip engaging in said U channel whereby said parts are held together.

3. An electrical connecting device comprising a casing formed of a plurality of parts and having a substantially circular channel formed therein adjacent to one end of said device and a substantially U-shaped channel formed therein adjacent the other end of said device, portions of said channels being located in each of said parts, a spring ring engaging in said circular channel and a spring clip engaging in said U-channel, whereby said parts are held together, the plane of said clip being perpendicular to the plane of said ring.
- 10 15 20

In testimony whereof I have signed my name to this specification.

MONROE GUETT.
